DESIGN FOR A SAFETY RAZOR BLADE HONE

Jan de Swart, Los Angeles, Calif., assignor of one-half to C. Bland Jamison, Los Angeles, Calif.

Application October 11, 1943, Serial No. 111,338

Term of patent 7 years

To all whom it may concern:

Be it known that I, Jan de Swart, a subject of the Queen of the Netherlands who has declared his intention of becoming a citizen of the United States, residing at Los Angeles, in the county of Los Angeles and State of California, have invented a new, original, and ornamental Design for Safety Razor Blade Hone, of which the following is a specification, reference being had to the accompanying drawing, forming a part thereof.

In the drawing: Fig. 1 is a perspective view; Fig. 2 is a top plan view; Fig. 3 is a side view and Fig. 4 is an end view of a safety razor blade hone, showing my new design.

I claim:

The ornamental design for a safety razor blade hone, as shown.
